UNITED STATES PATENT OFFICE

166,888

COMBINATION VENDING AND DISPLAY
DEVICE FOR HAIR CUTTERS

Abraham N. Spanel, Princeton, N. J., assignor to Cutler Corporation, Wilmington, Del., a corporation of Delaware

Application February 11, 1952, Serial No. 18,470

Term of patent 14 years

(Cl. D52—2)

To all whom it may concern:

Be it known that I, Abraham N. Spanel, a citizen of the United States and a resident of Princeton, in the county of Mercer and State of New Jersey, have invented a new, original, and ornamental Design for a Combination Vending and Display Device for Hair Cutters, of which the following is a specification, reference being had to the accompanying drawing, forming part thereof, wherein:

Fig. 1 is a side elevational view; and

Fig. 2 is a top plan view of a combination vending and display device for hair cutters, showing my new design.

I claim:

The ornamental design for a combination vending and display device for hair cutters, substantially as shown.

ABRAHAM N. SPANEL.
